ELECTRIC ATTACHMENT FITTING

John Petry, Flushing, N. Y., assignor to Raylite
Electric Corp., a corporation of New York

Application August 5, 1941, Serial No. 405,459

9 Claims. (Cl. 173—361)

This invention relates to electric attachment fittings, such as cap-plugs and the manufacture thereof, said fittings serving to detachably connect portable electric appliances, lighting systems and the like, to an electric power supply outlet receptacle in the well understood manner.

Among the objects of the invention is to generally improve electric attachment fittings of the character described, which shall comprise few and simple parts assembled to form a neat appearing, compact, rugged structure, which shall be cheap and easy to manufacture, and which shall be practical and efficient to a high degree in use.

Other objects of this invention will in part be obvious and in part hereinafter pointed out.

The invention accordingly consists in the features of construction, combination of elements and arrangement of parts which will be exemplified in the construction and method of manufacture hereinafter described and of which the scope of application will be indicated in the following claims.

This application contains in part subject matter described and shown in my Letters Patent No. 2,244,527, issued June 3, 1941, for Current-tapping cap-plug fitting and like attachment devices.

In the accompanying drawings, in which is shown various possible illustrative embodiments of this invention,

Fig. 1 is a view showing a development plan layout of a plug cap terminal blade in the manufacture thereof embodying the invention;

Figs. 2 and 3 are front and side elevational views, respectively, of the terminal blade in completed form after being cut, folded and bent from the layout shown in Fig. 1;

Fig. 4 is a sectional view taken through a one-piece insulating body portion of the improved cap-plug showing the conductor wires and one blade in the assembled process;

Fig. 5 is a top plan view of the one-piece body portion shown in Fig. 4 before the assembly thereof with terminal blades;

Fig. 6 is a sectional view like Fig. 4 except that the attachment cap lug is shown completely assembled and connected in circuit with the conductor wires;

Figs. 7, 8 and 9 are cross-sectional views taken on lines 7—7, 8—8 and 9—9, respectively, in Fig. 6;

Fig. 10 is a view showing a development plan layout of modified form of a plug cap terminal

blade in the manufacture thereof embodying the invention;

Figs. 11 and 12 are front and side elevational views, respectively, of the terminal blade in completed form after being cut, folded and bent from the layout shown in Fig. 10;

Fig. 13 is a sectional view of the one-piece body portion of a cap plug adapted to be used in an assembly with terminal blades shown in Figs. 11 and 12;

Fig. 14 is a cross-sectional view taken on lines 14—14 in Fig. 13;

Fig. 15 is a sectional view taken through an attachment cap-plug with the body portion shown in Fig. 13 completely assembled with the terminal blades shown in Figs. 11 and 12 and connected in circuit with conductor wires, and

Fig. 16 is a cross-sectional view taken on line 16—16 in Fig. 15.

Referring in detail to the drawings and as shown in complete assembly in Fig. 6, 20 denotes an improved attachment cap-plug fitting constructed to embody the invention adapted to be connected with a conventional base board or flush outlet receptacle of a suitable electric power supply (not shown), in the well understood manner, through spaced terminal blades 21 extending from insulation body portion 22, said fitting 20 being applied to the ends of conductor wires 23 which in turn connect with some portable electric appliances (not shown), as is well known in the practical application of the invention.

The terminal blades 21 are preferably formed of sheet metal, such as brass or bronze having a thickness of substantially one-half of that required for the final structure and should preferably be sufficiently resilient to have inherent spring in single thickness and in double thickness to be rigid enough to withstand bending and rough usage as the projection portion of such blades 21.

The manufacture of said terminal blades 21 may be carried out as follows: The single thickness sheet metal from which the blades 21 are formed may be each substantially rectangular shaped, as for example, strip S, punched or blanked out as shown as in Fig. 1, with the upper portion U thereof provided if desired, with a circular opening 21a above a crease line, XX. The mid-portion M of said strip S below said line XX, however, is cut to form a downwardly extending tongue 21b, while the lower portion L thereof spaced from the tongue 21d is provided with punched slit formed with upper and lower pierc-

ing prongs 21c and 21d, respectively, spaced on opposite sides of another crease line YY, said lower portion also having another tongue 21e cut to extend down thereon, spaced from the prongs 21d.

When the upper portion U of strip S is down folded on the crease line XX so that said upper portion U extends along the mid-portion M, a bight at the leading end 21f is formed and by leaving said upper portion U slightly divergent with respect to the mid-portion M, a spring contact is provided which terminates just short of the plane of the upper face 22a of the insulating body portion 22 as shown in the assembly in Fig. 6.

The lower portion L is upfolded on the crease line YY so as to double the thickness and stiffen the base end 21g of the blade 21 and at the same time also arranges and locates the upper and lower piercing prongs 21c and 21d in a recessed superimposed spaced or staggered relation to terminate said base end 21g. Thus if the upper prongs 21c comprise a set of three sharp pointed teeth and the lower prongs 21d comprise a set of two of such teeth, then the above described folded structure provides a series of five spaced staggered teeth as shown in Figs. 2 and 9. The tongues 21b and 21e may each be bent or sprung out of the planes of the mid-portion M and lower portion L, respectively, from opposite sides, so that the downwardly extending tongue 21b may serve as a contact means for connecting with the ends 23a of conductor wires 23 and so that the tongue 21e, upwardly extending from the up-folded lower portion L, may serve as a spring wedging means for irremovably securing the blade base in anchored position in the body portion 22, all as hereinafter described and shown in Fig. 6.

The insulating body portion 22 of the fitting 20 preferably is a one-piece structure of suitable shape and formed of so-called "plastics," as for example, a phenol-condensate product or the like moldable substances which provides a rigid finish structure.

As shown in Figs. 4, 5 and 6, the blades 21 are mounted and secured to extend upwardly from the top side 22a of body portion 22, the base ends 21g of said blades 21 being fitted into spaced sockets or cavities 22b extending in from said top side 22a. Said sockets 22b are each molded with a shoulder or ledge 22c adjoining a wall 22d, said walls 22d merging in a tapered portion or end 22e to permit through passage of the separate leads of the conductor wires 23, the latter being inserted in a central passage 22f extending in from the bottom side 22g of the body portion 22 opposite the top side 22a. Walls 22h of the passage 22e may be in substantial alignment with the walls 22d of sockets 22b to facilitate the core molding operation in manufacturing the body portions 22 to provide branch communication between the passage 22f and spaced sockets 22b.

With the blades 21 manufactured as above described as shown in Figs. 1 to 3, the fitting 20 may have the parts assembled and connected with the conductor wires 23 by inserting the ends 23a of a conductor wire lead from the body portion lower side 22g through the passage 22f and into the branched sockets 22b. If desired, said ends 23a are bared of insulation for a short distance and are preferably extended to approximately above the level of the body portion top side 22a as shown in Fig. 4. The blades 21 can now be fitted into the sockets 22b from said top side 22a and are pushed down until the piercing prongs 21c

and 21d at the base end 21g of the blades 21 cut through the insulation of the conductor wires 23 and make electric contact connection with the stranded core 23b as shown in Fig. 9. This cutting takes place when conductor wires 23 are forced against the bottom of the sockets 22b, and when the tongue 21e is sprung in moving from the position shown in Fig. 4 to a wedging position under the body portion ledge 22c for irremovably anchoring the blade base 21g rigid in the sockets 22b. The tongue 21b during the above described anchoring operation may enter a groove 22m provided to extend along each socket 22b to contact and electrically connect with the conductor

wire end 23a which occupies the said groove 22m and at the same time engages said end 23a for firmly wedging the conductor wire 23 about the blade ends 21g as shown in Figs. 6 and 8. Thus, two electrical connections are provided between the blade ends 21g and the conductor wire 23. The blade portions U terminating short of the body portion side 22a provide spring adjustment for taking up variation in receptacle outlet plug-in connections.

In Figs. 10 to 16, inclusive, there is shown another embodiment of the invention in the manufacture and construction of cap-plug fitting 120, having the blades 121 thereof formed of single thickness material, as strips S1, which are similar in shape and size to strip S described above in connection with fitting 20 but may be made to correspond to the layout shown in Fig. 10.

The strip S1 also may comprise an upper portion U1 having an opening 121a above a crease line XX, a mid-portion M1 having a slit forming a downwardly extending piercing prong 121b above a crease line YY while a lower portion L1 is provided on upwardly extending piercing prong 121c below said crease line YY so as to provide a central split between spaced sections 121e in the manner hereinafter described and shown in Fig. 11. Opposite edges on the lower portion of the mid-portion M1 and upper part of lower portion L1 may be cut as at 121j to provide spurs 121k which are adapted to be anchored under shoulders 122d of an insulating body portion 122 as shown in Fig. 16.

The manufacture of terminal blades 121 is carried out in a manner similar to that for producing blades 21 by punching or cutting strip S1 with the layout shown in Fig. 10 and then down folding the upper portion U1 on crease line XX to provide a bight at the leading end 121f. By leaving said upper portion U1 slightly divergent with respect to the mid-portion M1, a spring contact is provided which terminates just short of a plane of the upper face or side 122a of the body portion 122 like the construction in blades 21 and as shown in Figs. 12 and 15.

The lower portion L1 is upfolded on crease line YY so as to double the thickness and stiffen the base end 121g of the blade 121 and at the same time also arrange and locate the piercing tongues 121b and 121c in spaced relation as shown in Fig. 11. The tongue 121b may be bent or sprung out of the plane of the mid-portion M1 so that said downwardly extending tongue 121b may serve as a contact means for connection with ends 23a of conductor wire 23 as shown in Fig. 15. The base end 121g of each blade 121 formed is seen in Figs. 11 and 16 to have spaced apart sections 121e each terminated by a spur 121k thus forming a structural portion which is similar in all respects to the base end of the blades fully

described and shown in my aforementioned patent.

The insulating body portion 122 of fitting 120 like body portion 22 of fitting 20 may also be made of a "plastic" molded substance, and as shown in Figs. 13 to 16, inclusive, the blades 121 are mounted to extend upwardly from the body portion top side 122a, the blade base ends 121g being fitted into spaced sockets or cavities 122b extending in from said top side 122a. The bottom end of each socket 122b is molded with an integrally formed upwardly projecting wedge 122c which is arranged and constructed to spread the spaced sections 121e when the base ends 121g are inserted fully into the socket 122b as shown in Fig. 16. The side walls of the socket 122b extend parallelly in from said top side 122a, the width of said socket being enlarged at the inner ends of said side walls, that is, cut back for a length substantially equal to the wedge 122c to provide shoulders 122m and anchoring pockets for expanding the split base end 122g as shown in Figs. 14 and 16.

The inner wall 122d of the sockets 122 between side walls merge into a tapered portion or end 122e to permit through passage of the separate leads of the conductor wires 23, the latter being inserted in a central passage 122f extending in from the body portion bottom side 122g opposite top side 122a. The walls 122h of the passage 122f may be in substantial alignment with the upper end of the socket wall 122d to facilitate the core molding operation in manufacturing the body portion 122 to provide a branch communication between the passage 122f and spaced socket 122b.

With the blades 121 manufactured as above described and shown in Figs. 10 to 12, the fitting 120 may have the parts assembled and connected with the conductor wires 23 by inserting the end 23a thereof in from the body portion lower side 122g through passage 122f and into branched sockets 122b. Like in the assembly of fitting 20, the ends 23a are preferably extended to approximately above the level of the body portion top side 122a. The blades 122 may then be inserted into the sockets 122b from said top side 122a and are pushed down until the piercing prongs 121c between the sections 121e of the blade base end 121g cut through the insulation of the conductor wires 23 and make electrical contact connection with the stranded core 23b as shown in Fig. 16. This cutting takes place when the conductor wires 23 are forced against the wedge 122c at the bottom of the sockets 122b. Said wedges 122c simultaneously enter the split in the base ends 122g and cam the sections 121e laterally into the pockets and under the shoulders 122m making an irremovable firm anchorage without scoring or otherwise scratching the walls of said pockets other than tightly squeezing or perhaps biting the spurs 121k into the pocket walls to form a rigid attachment. The piercing tongues 121b during the above described anchoring operation contact and electrically connect with the conductor wire ends 23a and at the same time spreads said ends 23a which occupy grooves 122n provided to extend along sockets 122b to firmly wedge the conductor wires 23 about the blade end 121g as shown in Fig. 15. Thus, here again two electrical connections are provided between the blade ends 121g and the conductor wires 23 while the blade portion 121 which terminates short of the body portion top side 122a provides a spring adjustment like that described above for the blades 22 of fitting 20.

It will thus be seen that there is provided fittings whereby the several objects of this invention are achieved and which are well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. In a cap-plug attachment fitting of the character described, a blade formed of a strip of single thickness material having a slit wholly within an end portion thereof, a fold extending transverse the slit to provide a double thickness base for the blade, the contour edge of said slit providing a recess at said fold of the base, and piercing prongs integrally projecting from the contour edge of said slit in the same relative direction within said recess just short of the fold, alternate prongs being formed on oppositely located edge portions of said slit.

2. An electrical fitting of the character described comprising a one-piece rigidly molded body and terminal blade mounted to extend therefrom, said body having an opening extending in from one side thereof and parallelly aligned sockets extending in from another side of said body so constructed and arranged to communicate as branches with said opening, said blades each being formed of single thickness material having a lower portion provided with a slit and a folded end extending transverse said slit to provide a base of double thickness for the blade with recessed edges adjacent the fold, said blade bases having integrally formed spring portions, conductor wires passing through said opening and having bared ends thereof extending into the branch sockets, shoulders within said sockets for engaging with the spring portions on fully inserting the blade bases into the sockets to irremovably anchor said bases therein, said recessed edges on anchoring of the blade bases engaging the conductor wires for electrically connecting the latter with the blades, said sockets having grooves extending the length thereof wherein said bared ends of the conductor wires are located, and contact making means integrally formed from the blade bases and bent out of the plane of said bases to extend into said grooves engaging said conductor wire end portions to electrically connect the latter with the blades when in anchored position.

3. The electrical fitting defined in claim 2 in which said recessed edges include prongs extending within the recess for piercing through the conductor wire insulation.

4. The electrical fitting defined in claim 2 in which said recessed edges include spaced sets of piercing prongs extending within the recess, alternate prongs being formed on opposite integral edge portions of said slit.

5. An electric fitting of the character described comprising a one-piece rigidly molded body and terminal blades mounted to extend therefrom, said body having an opening extending in from one side thereof and parallelly aligned sockets having wall grooves extending in from another side of said body so constructed and arranged to communicate as branches with said opening, said blades each having integrally formed spring portions and piercing prongs at the bases thereof,

conductor wires passing through said opening and into the branch sockets, said wire having bared ends terminating in said grooves, shoulders within said sockets for engaging with the spring portions on fully inserting the blade bases into the sockets to irremovably anchor said bases therein, said piercing prongs engaging the conductor wires for electrically connecting the latter with the blades, and contact making means integrally formed from the blade base and bent out of the planes of said bases to extend into said grooves for engaging said conductor wires bared end to electrically connect the latter with the blades when in anchored position.

6. The electrical fitting defined in claim 5 in which said blade bases have recesses on the edge portion of which piercing prongs are integrally formed to extend in the same general direction wholly therein.

7. The electrical fitting defined in claim 5 in which said piercing prongs are located in a recess provided at the end of each blade base, adjoining prongs being formed to extend from widely spaced edge portions of said recess.

8. An electrical fitting of the character described comprising a one-piece rigidly molded body and terminal blades mounted to extend therefrom, said body having an opening extending in from one side thereof and parallelly aligned sockets extending in from another side of said body and communicating with said opening, said

5   sockets having undercut pockets at their inner ends, said blades each having expandable base portions including piercing prongs therebetween, each blade being decreased in cross-sectional area
10   at a mid-portion to enlarge ends thereon fitted into said sockets, conductor wires having bared end passing through said opening and into each socket, the wire passing between said base portions engaged by some of said piercing prongs electrically connecting with said blades, camming means forming part of the walls of said sockets for engaging and expanding said base portions so constructed and arranged that said expanded blade portions grip the ends thereof in
15   the pockets to irremovably anchor the blades in rigidly mounted positions and for confining the conductor wires to positively engage with said last mentioned piercing prongs on said expansion said blade ends while a remainder of said piercing prongs is located to electrically connect with said bared end of the wire at a spaced distance from said first mentioned electrical connection.
20   9. The electrical fitting defined in claim 8, in which said blades are each constructed of single thickness material having a lower portion provided with a slit within an end portion thereof and a fold extending transverse the slit to form said expandable base of double thickness with said prongs on recessed edges of the slit.

JOHN PETRY.
